(73) Assignee: **Harvatek Corporation** (TW)

(57) **CLAIM**

(**) Term: **14 Years**

I claim the ornamental design for a metal base design for surface mount device LED (lighting emitting diode), as shown and described.

(21) Appl. No.: **29/214,779**
(22) Filed: **Oct. 12, 2004**

DESCRIPTION

(51) LOC (8) Cl. 13-03

FIG. 1 is a 3D of top view of a metal base design for surface mount device LED showing my new design;

(52) U.S. Cl. D13/180

FIG. 2 is a front view thereof;

(58) Field of Search D13/180, 182;

FIG. 3 is a rear view thereof;

174/52.4; 257/99, 91, 431, 433, 666, 81;

FIG. 4 is a left side view thereof;

315/169.2, 169.3; 361/767; 362/249, 582;

FIG. 5 is a right side view thereof;

372/34; 438/124

FIG. 6 is a top view thereof;

FIG. 7 is a bottom view thereof;

FIG. 8 is a 3D of bottom view thereof; and,

FIG. 9 is a perspective view thereof in use.

The broken line showing of the environment is for illustrative purpose only and forms no part of the claimed design.
